[57] ABSTRACT

Miniaturized support for clockworks which have chain-operated movements, wherein the front and rear plates of the clock can be made of small size and are joined to each other by means of only a pair of struts, one of which is so constructed to surround the axle of the long hand of the clock.

CLOCKWORK MOVEMENT SUPPORT**BACKGROUND OF THE INVENTION**

The present invention relates to clockwork movements of wall clock and, in particular, to movements wherein the front and rear base plates of the clockwork are retained by means of only two supporting struts.

In certain clockwork movements of conventional and especially chain-operated wall clocks, the square-shaped front and rear base supporting plates are usually joined together by means of struts disposed at each of the four corners of the base plates. The long hand is then positioned in the center of the base plates, that is to say, it is mounted so that all the struts are located outside of the wheel block of the clock. As a result, with such an arrangement it is considerably difficult to make base plates of sizes smaller than predetermined ones.

SUMMARY OF THE INVENTION

It is, therefore, the primary object of the present invention to provide a small-size clockwork movement for wall clocks wherein the supporting base plates are simplified and are suitably miniaturized.

It is another object of the invention to provide in said clockwork movement front and rear base plates with a reduced number of joining struts.

DRAWINGS

These and other objects of the invention will become more apparent from the following detailed description thereof and from the accompanying drawings in which :

FIG. 1 is a cut-out perspective view of a first embodiment of a clockwork movement of a wall clock embodying the invention ; and

FIG. 2 is a simplified perspective view of another embodiment of the clockwork movement of FIG. 1.

DETAILED DESCRIPTION OF THE INVENTION

A preferred embodiment of the invention will now be described with reference to the drawing of FIG. 1.

Referring to FIG. 1, the clockwork movement comprises a front base plate 1 and a rear base plate 2.

A strut 3 joins the front and rear base plates 1, 2. Strut 3 is mounted centrally and adjacent the upper edge of the two plates, as shown in the figure. A tubular strut 4 further joins the front and rear base plates to each other, this strut 4 being positioned substantially opposed to strut 3 and adjacent the lower edge of the two plates. The struts 3 and 4 serve to fix the base plates in a parallel position to each other, the stem of at least one strut being preferably of larger diameter. The axle 5 of the long hand 14 extends frontally through the tubular strut 4 and is supported thereby.

To complete the clockwork, there are provided a weight 6 connected to a chain wheel 8 through a chain 7; a first wheel 9 secured to the axle which supports the chain wheel 8; a second wheel 10, a ratchet wheel 11, a ratchet 12, a transmission wheel 13, a short hand 15, a

short hand axle 16, and a toothed wheel 16' mounted on the short hand axle 16.

The clockwork movement according to the invention is constructed as mentioned hereinabove, so that the axle 5 of the long hand 14 is positioned concentrically within the tubular strut 4 separating base plates 1 and 2. These two plates are supported by the two single struts 3 and 4. Thus, the whole movement, particularly the front and rear base plates may be, as a result, miniaturized. Furthermore, the tubular strut 4 is so constructed that it will surround the axle 5 of the long hand 14.

The described other, illustrated members are part of the conventional counting system of the clock and are outside the scope of the invention. Similarly outside the scope are chain wheel 17, chain 18 and weight 19 which are part of the beating system. All of these respective members are not notably different from those in a conventional wall clock, so that a detailed description or a schematical representation thereof may be omitted.

Referring now to FIG. 2, which shows another embodiment of the invention, reference numeral 20 denotes a variance of strut 4 of FIG. 1, showing a strut consisting of a small plate as a replacement for the tubular strut 4 of FIG. 1. The bent or folded end portions 21 and 22 at both terminals of the plate strut 20 are bifurcated and secured to the front base plate 1 and the rear base plate 2 respectively. Apertures 23 and 24 are drilled in the front and rear base plates between the bifurcated parts of the folded ends 21 and 22. These bores 23 and 24 serve to support the axle 5 of the long hand, as in FIG. 1. Furthermore, the plate strut 20 is so shaped that the axle 5 is positioned between the bifurcations of the strut.

What is claimed is :

1. In a clockwork movement for wall-type clocks, the improvement which comprises
  - a. A front base plate;
  - b. A rear base plate parallel to said front base plate;
  - c. A first strut rigidly separating said two plates and positioned therebetween, centrally along the upper edges of said plates;
  - d. A second strut rigidly separating said two plates and positioned therebetween, opposite said first strut along the lower edges of said plates;
  - e. An axle positioned within said second strut and protruding frontally from said front plate for supporting said clock's long hand.
2. The improvement according to claim 1, wherein said second strut is tubular and concentrically surrounds said axle.
3. The improvement according to claim 2, wherein said first strut has a larger diameter than said second strut's.
4. The improvement according to claim 1, wherein said second strut is a plate having terminal folded and bifurcated ends, said ends being secured to at least one of said plates at said edge thereof, said axle being located axially between the bifurcations.
